US0D1038153S

(12) **United States Design Patent** (10) **Patent No.:** **US D1,038,153 S**
(45) **Date of Patent:** **** Aug. 6, 2024**

(54) **DISPLAY SCREEN OR PORTION THEREOF WITH GRAPHICAL USER INTERFACE**

(71) Applicant: **Chainalysis, Inc.**, New York, NY (US)

(72) Inventors: **Patrick Curran**, Silver Spring, MD (US); **Michael Gronager**, Miami, FL (US); **Jacob Illum**, Ellicott City, MD (US); **Monica Santos**, New York, NY (US); **Pankaj Singh**, Hovedstaden (DK)

(73) Assignee: **Chainalysis, Inc.**, New York, NY (US)

(**) Term: **15 Years**

(21) Appl. No.: **29/864,441**

(22) Filed: **May 27, 2022**

(51) LOC (14) Cl. **14-04**

(52) U.S. Cl. **USPC D14/485**

(58) **Field of Classification Search**

(57) **CLAIM**

The ornamental design for a display screen or portion thereof with graphical user interface, as shown and described.

DESCRIPTION

The FIGURE is a front view of a display screen or portion thereof with graphical user interface showing our new design.

The peripheral uneven-length broken lines illustrate a display screen or portion thereof, and form no part of the claimed design. The even-length broken lines within the peripheral uneven-length broken lines illustrate portions of the graphical user interface that form no part of the claimed design.
